UNITED STATES PATENT OFFICE.

JOSEPH J. BENEDICK, OF CHICAGO, ILLINOIS.

VALVE-DRESSING TOOL.

1,233,302.

Specification of Letters Patent.

Patented July 17, 1917.

Application filed August 30, 1916. Serial No. 117,691.

To all whom it may concern:

Be it known that I, JOSEPH J. BENEDICK, a citizen of the United States, and a resident of the city of Chicago, county of Cook, 5 and State of Illinois, have invented certain new and useful Improvements in a Valve-Dressing Tool, of which the following is a specification.

My present invention relates to improvements in valve dressing tools, and has special reference to the provision of such a tool for dressing the conical or inclined valve seating surface of pop-valves such as are widely used in internal combustion engines.

10 When the valve seat is originally prepared for the reception of the valve or when it is resurfaced to remove a badly worn or pitted condition, it is obvious that the valve seating surface must be given the exact size 15 and inclination of the seat. This may be easily done with my present tool by placing the tool with which the valve seat was worked in my tool and adjusting the cutting member to the size and inclination thereof.

20 25 If the trouble is entirely with the seating surface of the valve and not in the valve seat itself, the proper inclination can be found by placing the old valve in my tool and then making the necessary adjustment 30 to secure the proper taper and to take off in the dressing operation sufficient metal to properly resurface the part.

There is more or less chattering or vibration between the tool and the work in tooling metal in the ordinary manner which results in an uneven surface. This has to be avoided in valve dressing and I have provided adjustments to avoid chattering in my present tool. These adjustments comprise 35 40 facilities for presenting the tool to the work in the manner hereinafter described, and for securing a nice fit for the valve stem which will secure its even rotation. I have also provided a simple means for setting the tool 45 to take off a predetermined amount of the metal, and no more, so that after the tool is set by an experienced person, the resurfacing may be done by anyone who may be ordered to do it, without the danger of taking 50 off too much metal and ruining the valve.

Other objects of my invention are to provide the above facilities in a simple structure, inexpensively made and easy to adjust and operate.

55 I attain the above objects by means of the

structure illustrated in the accompanying drawing, in which,—

Figure 1 is an elevation of my invention.

Fig. 2 is a plan of the structure shown in Fig. 1.

Fig. 3 is a vertical sectional view through the adjustable bushing.

Fig. 4 shows the angular presentation of the tool to the work; and

Figs. 5 and 6 are respectively an elevation 65 and a plan of a modified form of tool and work-holding bracket.

Similar reference characters refer to similar parts throughout the several views.

My tool preferably comprises a body portion, 6, having at least two parallel sides, 7, and, 8, so as to permit of its being readily held in a vise. This body portion is longitudinally bored and at least partially internally threaded, as at 9, to receive the internally and exteriorly threaded sleeve, 10, which preferably has provided at one end a knurled annular extension, by means of which it may be screwed farther into or out of the bore of the body portion. Near the top of the body portion is a transverse cut, 11, which runs through to the central bore, and likewise a vertical cut, 12, which runs through to the bore from the top of the body portion to the transverse cut, 11. The partially detached part of the body portion, 13, formed by the cuts, 11, and 12, is bored at 14 and this bore is carried through into the adjacent portion of the body portion at 15, and the portion of the bore in the body portion is tapped to receive a set screw, 16, by means of which the partially detached portion, 13, of the body may be constricted about the sleeve, 10, to secure it in adjusted position. Mounted within the top and bottom of the sleeve, 10, are two exteriorly tapered and threaded bushings, 17, and 18, the top one, 17, being partially longitudinally slit, as at 19, and the bottom bushing, 18, being completely longitudinally slit, as at 20. It will be seen that by screwing these bushings, 17, and 18, farther into or out of the sleeve, 10, a very nice fit may be secured for the valve stem.

Extending laterally from the body portion, 6, is the tool bracket, 21, the face, 22, of which is inclined to the axis of the bushings, 17, and 18. The bracket, 21, is bored at 23 and secured to its face through the bore by means of a suitable screw is a cylin- 110

drical tool holder, 24, having a transverse tool receiving aperture, 25, therein and a set screw, 26, extending into the aperture to secure the tool in suitable or desired position. The inclination of the cutting edge of the tool to correspond with the correct taper of the valve seating surface is secured by rotating the tool holder upon its axis, and the inclination of the face, 22, of the 10 tool bracket, 21, and the bottom of the tool aperture, 25, is such as to present the cutting edge of the tool, not radially, or at right-angles, but obliquely to the moving surface to be finished. This particular presentment 15 of the tool to the work secures a scraping action which obviates the chattering and secures a very much finer surfacing than can be secured by the ordinary presentment of the tool, as in a lathe, even when the tool is 20 adjusted to take a very fine cut.

It will also be noted that the cutting edge of the tool extends not directly across the seating surface, but obliquely thereof, as shown in Fig. 4, which is also desirable in 25 securing a fine surface.

In the modified form shown in Figs. 5 and 6, the cast body portion, 6, with the tool bracket, 21, is replaced by a piece of boiler plate, 27, or other sheet metal of suitable 30 thickness. One end of this plate, 27, is bent to form a loop or round casing, 28, for the sleeve, 10, but instead of being threaded, the looped edge is extended parallel with the body main portion, 27, of the plate and is 35 secured thereto by screws, 29. By screwing up the screws, 29, the sleeve, 10, may be rigidly secured in place without threading the inside of the loop, 28. By manipulating the screws, 29, a very nice fit can be secured directly between the valve stem and the loop, 28, and the sleeve, 10, may be dispensed with.

Opposite the loop or casing, 28, the plate, 27, is bent at a suitable angle and bored to

form a tool holding wing, 30, to which the 45 tool holder, 24, is secured in the same manner it is secured to the tool bracket, 21, in the previously described form.

What I claim is:—

1. A valve dressing tool comprising means 50 for rotatably receiving a valve stem, and separate means adjustably carried by said first mentioned means for holding a tool obliquely with respect to the path of rotation about the axis of said valve stem receiving means and with the cutting edge of 55 said tool in a plane at a desired angle with said axis.

2. In a valve dressing tool adjustable means for rotatably receiving a valve stem 60 comprising a casing an interiorly threaded sleeve, means for adjustably securing said sleeve in said casing, and a plurality of exteriorly tapered and threaded bushings having transverse slots therein adapted to screw 65 into said sleeve.

3. In a valve dressing tool adjustable means for rotatably receiving a valve stem comprising an interiorly threaded casing and an interiorly and exteriorly threaded 70 sleeve, means for adjustably securing said sleeve in said casing, and a plurality of exteriorly tapered and threaded bushings having transverse slots therein adapted to screw 75 into said sleeve.

4. In a valve dressing tool means for rotatably receiving a valve stem, a tool holding wing disposed in a plane at an angle to any plane of the axis of said valve receiving means, a tool holder and means for adjustably securing said tool holder to said wing.

Signed at Chicago, county of Cook, and State of Illinois, this 26th day of August, 1916.

JOSEPH J. BENEDICK.
